UNITED STATES PATENT OFFICE.

ARTHUR B. WARING, OF YONKERS, NEW YORK.

HAT-BODY-FORMING MACHINE.

SPECIFICATION forming part of Letters Patent No. 723,954, dated March 31, 1903.

Application filed May 8, 1902. Serial No. 106,427. (No model.)

To all whom it may concern:

Be it known that I, ARTHUR B. WARING, a citizen of the United States of America, and a resident of Yonkers, county of Westchester, 5 and State of New York, have invented certain new and useful Improvements in Hat-Body-Forming Machines, of which the following is a specification.

This invention relates to an improvement 10 in hat-body-forming machines.

In each forming-machine the cone on which the hat-body is formed is placed on a wooden platform or bed, which in turn is situated on a turn-table which revolves when the machine 15 is in motion, with the object of obtaining the even distribution of the fur on the surface of the said cone. My invention relates particularly to improvements in these parts of the machine—namely, the bed and cone. In the 20 center of the said turn-table and wooden platform upon it is a central opening which permits the suction of air created by a fan or other apparatus to draw the fur upon the perforated surface of the cone placed above this 25 central opening and hold it there until the cone, with the hat-body upon it, is covered or wet down and removed from the machine. The cones and platforms or beds for supporting the cones hitherto in use in hat-body-forming machines were defective in that the joint 30 between the cone and its support or bed is often uneven, the edge of the cone and the bed becoming worn in use by the constant removal of the cone while the table is revolving, and this unevenness will leave a space 35 between the cone and the platform or bed, with the result that some of the fur floating in the chamber inclosing the cone is drawn through this space and below the turn-table 40 into the suction apparatus instead of being deposited onto the perforated surface of the cone, thereby lowering the weight of the hat-body beyond that which was originally intended and making the hats of uneven weight. 45 The amount of reduction in weight will depend upon the size of the space between the cone and the bed, as much more fur than otherwise will be drawn through under the cone if this space is increased. I have found that 50 a very trifling space between the cone and the platform or bed upon which it rests will be sufficient to cause considerable loss of fur

and material variation in the weight of the hat-body.

It is the object of my present invention to 55 overcome these defects in the cone and the platform which supports the same and to make the joint at all times practically air-tight; and to this end my invention consists of certain features of construction and combinations of 60 parts to be hereinafter described and particularly claimed.

In the accompanying drawings, Figure 1 is a view of a cone and support or bed, half in elevation and half in section, showing one 65 form of the invention. Fig. 2 is a vertical central section of another form of the invention. Figs. 3 and 4 are rear views in which the wire-gauze or perforated surface is omitted.

The platform or bed which supports the 70 cone is usually made of wood, although not necessarily, and is caused to rotate on an iron turn-table; but as the means of rotation have nothing to do with the present invention, consequently only a support or bed A and a cone 75 B are shown. Each cone is composed of a body portion B, of perforated metal, either sheet-copper or wire-gauze, provided with a ring-shaped base portion C, usually made of sheet-copper, with diametrically opposite handles 80 C' C' for the purpose of enabling the attendant to withdraw the cone from the revolving table. The described parts are well known, and I do not, therefore, claim the same. After continued use the upper surface of the bed or 85 support A becomes unevenly worn, and even in new supports or beds the surface is not always even and fitted closely to the lower edge of the cone which rests thereon; also the lower edge of the base-ring of the cone becomes 90 unevenly worn after use. The bed or support might with great care be made to fit or suit one pair of cones; but as different sizes of cones must be used, according to the quality of hat that is being formed, it would be practically 95 impossible to get a platform or bed which would make a tight joint between the various-sized cones and support. I have shown in Figs. 1 and 3 one example of my invention which will counteract these defects, for which 100 purpose there is attached to the base-ring of the cone by means of rivets or other suitable fastenings an exterior annulus D, of rubber or other flexible and suitable material, the

lower edge of which is free and loose and protrudes below the lower edge of the base-ring C. A yielding edging for the cone is thereby formed. When the cone is placed 5 upon the table or platform, its weight is transmitted to the table through the flexible supporting-annulus D, the free or loose portion of which yields to the unevenness of the upper surface of the platform or bed, 10 and thereby forms a practically air-tight joint all around the base of the cone. The loose flabby portion of the flexible annulus is drawn tight down by the suction exerted, and any space or opening which might otherwise exist is closed.

In Figs. 2 and 4 a modification is shown in which the cone appears as usual. In this form of invention the bed A is provided with an annular recess or depression around the 20 suction-opening, and into this recess projects the free and loose inner periphery of a flexible annulus E, the outer periphery of which is suitably secured to the upper surface of the table at e. In this form of invention the 25 base of the cone rests upon the cushioning or loose flap portion of the flexible annulus E, and as the said annulus is of a yielding nature it will conform to any unevenness of surface and a practically air-tight inclosure 30 will be formed all around the lower edge of the cone. The flexible annulus or its equivalent thereby produces a packed joint.

With the construction shown in Figs. 1 and 3 any desired size of cone may be supported 35 with a practically air-tight joint between the cone and the platform or bed upon which the

cone rests, while with the construction shown in Figs. 2 and 4 it is preferable, in order to permit this air-tight contact with various sizes of cones, to leave a suitable portion of 40 the flexible annulus E free and detached.

By the described constructions any of the fur or other fibrous material is prevented from being sucked in under the cones. The loss of fur with former machines and the previous method of supporting cones while forming the hat-bodies often amounted to considerable in the course of the day's production and, moreover, rendered the weight of the predetermined hat-body uncertain.

45

50

What I claim as new and of my invention is—

1. The combination of a cone-bed of a hat-body-forming machine, a cone, and a flexible annulus attached at one periphery to one of 55 said parts and free at the other periphery to give a yielding support to the cone, substantially as described.

2. A cone-bed of a hat-body-forming machine, having a yielding or flexible surface, 60 substantially as described.

3. The combination of a cone-bed of a hat-body-forming machine, a cone, and a yielding surface between the two, substantially as 65 described.

Signed by me at Yonkers, New York, this 3d day of May, 1902.

ARTHUR B. WARING.
